(57) **CLAIM**

The ornamental design for a display panel or screen with a graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front elevational view of a display panel or screen with a graphical user interface showing our new design; The broken lines showing a display panel or screen, and other elements form no part of the claimed design. Dot-dash broken lines showing a portion of the display panel or screen define the boundaries of, but are not included in, the claimed design. The white dash lines within the dot-dash lines and the areas within the white dash lines show environment that form no part of the claimed design.
